UNITED STATES PATENT OFFICE.

JOHN C. MERRILL, OF SAN MARTIN, CALIFORNIA.

PUMP.

1,254,522.

Specification of Letters Patent. Patented Jan. 22, 1918.

Application filed June 22, 1916. Serial No. 105,222.

To all whom it may concern:

Be it known that I, JOHN C. MERRILL, a citizen of the United States, residing at San Martin, in the county of Santa Clara and State of California, have invented a new and useful Pump, of which the following is a specification.

The present invention appertains to pumps, and aims to provide a novel and improved mechanism for pumping water or other liquid from a well.

It is also the object of the invention to provide a pump of simple and inexpensive construction, consisting of but few parts, and operable in a simple yet effective manner.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein—

Figure 1 is a vertical section of the pump, portions being broken away and others being shown in elevation.

Fig. 2 is an elevation of a second form of the invention, portions being broken away.

Fig. 3 is an enlarged sectional detail of the pump illustrated in Fig. 2.

Fig. 4 is an enlarged detail of the actuating mechanism.

In carrying out the invention, reference being had particularly to Fig. 1, the lower end of the eduction pipe 1 for the water or other liquid is connected by a coupling or union 2 with the upper end of a lower vertical pipe 3, an annular valve seat 4 being provided within the pipe 3 adjacent its upper end and a check valve 5 being seatable thereon to support the column or head of water within the pipe 1.

Threadedly or otherwise engaged upon the lower end of pipe 3 is a ring 6 having a lower inturned flange or lip 7 providing a valve seat, and a second ring 8 is threadedly or otherwise engaged upon the pipe 3 immediately above the ring 6. The two rings 6 and 8 are employed for clamping leather or equivalent cups 9 therebetween which extend in opposite directions. The flange 7

provides a seat for a check valve 10, the leather of which is clamped between the lower end of the pipe 3 and the flange 7.

A vertical reciprocating pump cylinder 60 or barrel 11 surrounds the lower portion of the pipe 3 and the rings 6—8 and cups 9 provide a stationary piston fitting snugly within the barrel 11 which is reciprocated vertically by means of a vertical pump rod 65 12 having its lower end bifurcated or forked so as to straddle the pipes 1 and 3. The lower terminals of the prongs 13 of the fork are bolted or otherwise fastened, as at 14, to the upper end of the cylinder 11 and a ring 70 15 within the upper end of said cylinder. The pump rod 12 is reciprocated by any suitable mechanism.

Threadedly or otherwise engaged upon the lower end of the cylinder 11 is a ring 75 or band 16 having a lower inturned flange or lip 17 forming a seat for a check valve 18 which has its leather clamped between the lip 17 and the lower end of the cylinder 11. Thus, the lower ends of the pipe 3 and 80 cylinder 11 are provided with upwardly opening check valves.

It will be noted that the rod 12 is upon the exterior of the pipe 1, and that no packing is necessary for the pump rod, the 85 only contacting portions of the pump being the cylinder 11 and piston carried by the lower end of the pipe 3. When the cylinder 11 is moved downwardly, the valve 10 remains seated, and the chamber within the 90 lower portion of the cylinder between the piston and valve 18 being enlarged, will create a partial vacuum therein, thus opening the valve 18 and sucking the liquid into the lower portion of the cylinder. Then, 95 when the cylinder is moved upwardly, the valve 18 remains seated by the pressure, and the liquid is raised and forced past the valve 10 into the pipe 3, thereby raising the 100 column of water in the pipes 1 and 3. Thus, as the cylinder 11 is reciprocated, it elevates the water or other liquid.

In Fig. 2, a double acting pump is illustrated, the two pipes 3 being connected with the coupling 2 by means of a Y-coupling 19, there being two of the cylinders 11 which reciprocate in opposite directions.

The operating mechanism for the cylinders 11 embodies a concrete or other suitable base 20 provided upon the surface of 110 the soil surrounding the well, and upon which sills 21 are mounted, said sills car-

rying a frame 22. Said frame 22 has guides 23 for the upper ends of the pump rods 12 and said pump rods are connected by pitmen or connecting rods 24 with a pair of gear wheels 25. Said gear wheels mesh with pinions 26 secured upon the shaft 27 of a turbine 28 supplied with water, steam or other motive fluid by means of a pipe 29 having a valve 30 for controlling the flow of fluid. When the turbine 28 is operated, it rotates the gears 25, whereby the pitmen 24 impart opposite reciprocatory movement to the rods 12 for actuating the pistons 11, thereby to provide a double acting pump, so that a practically continuous upward flow of water is provided.

Having thus described the invention, what is claimed as new is:—

A pump embodying a vertical pipe, a pair

of rings threaded upon the lower end thereof, a pair of packing cups clamped between said rings and extending in opposite directions, a vertical reciprocatory cylinder movable on said packing cups, the lower ring having an inturned flange below the lower end of said pipe, a check valve clamped by said flange against the lower end of said pipe, said flange providing a seat for said valve, and a check valve carried by the lower end of the cylinder.

In testimony that I claim the foregoing as my own, I have hereto affixed my signature in the presence of two witnesses.

JOHN C. MERRILL.
